[57] CLAIM

The ornamental design for a coal burning stove, as shown and described.

DESCRIPTION

FIG. 1 is a front elevational view of one embodiment of a stove showing my new design;

FIG. 2 is a side elevational view thereof;

FIG. 3 is a rear elevational view thereof;

FIG. 4 is a bottom plan view thereof;

FIG. 5 is a top plan view thereof;

FIG. 6 is an elevational view of the opposite side thereof; and

FIG. 7 is a front elevational view of an alternate embodiment of a stove showing my new design, the other views thereof being identical to those shown in FIGS. 2—6.

FIG. 1

FIG. 2

FIG. 3

FIG. 7

FIG. 4
